UNITED STATES PATENT OFFICE.

JAMES EUGENE COCIIRANE, OF MALDEN, MASSACHUSETTS.

SELVAGE-SINGEING MACHINE.

SPECIFICATION forming part of Letters Patent No. 642,207, dated January 30, 1900.

Application filed April 22, 1897. Serial No. 633,238. (No model.)

To all whom it may concern:

Be it known that I, JAMES EUGENE COCH-
RANE, a citizen of the United States of Amer-
ica, and a resident of Malden, in the State of
Massachusetts, have invented a new and use-
ful Improvement in Selvage - Singeing Ma-
chines, of which the following is a specifica-
tion.

In the accompanying drawings, Figure 1 is
an elevation with part of the supporting-
frame in section. Fig. 2 is a plan view look-
ing from above down upon the machine and
showing the machine in operation, with a roll
of carpet passing through the machine and
with gas-jets in the position they occupy in
actual operation. Fig. 3 is a plan view look-
ing from above down on the machine, the roll
of carpet being removed and the gas-jets be-
ing shown in the position occupied by them
when not in actual operation; and Fig. 4 is a
drawing of details illustrating the mechanism
for protecting the selvage edges of the carpet
and for adjusting the same to different widths
of carpet.

My invention has for its object the use of a
gas or similar flame for the purpose of singe-
ing off the loose fibers of wool and other ma-
terial which exist along the selvages of car-
pet. As is well known, on leaving the loom
on which it is woven the surface and selvage
edges of the carpet are too rough to be pre-
sentable, and in particular with velvet car-
pets it is extremely uneven and unfit for mar-
ket. It has long been customary to run the
carpet after it leaves the loom through a
shearing-machine, which shears the pile-surface
of the carpet evenly; but it has been im-
practicable to use any form of shearing-ma-
chine to shear or clip the overhanging edges
of the pile at the selvage, and these edges
have generally been trimmed by hand in an
irregular and imperfect manner prior to the
stitching or sewing together of the carpet at
the selvage, and in consequence of the irregu-
larity of the selvage a ridge or irregular pro-
jection has generally existed in sewed carpets
as they are laid upon the floor. The mechan-
ism invented by me makes use of a suitable
gas-flame, which is caused to play upon the
selvage edges of carpet as the carpet is drawn
rapidly along, the selvage edges being suit-

ably protected from undue exposure to the
flame. I have found that with my improved
mechanism all rough projecting fibers are re-
moved and the selvage edges of the pile are 55
left uniform and regular, so that when the
carpet is sewed it is almost impossible to de-
tect the join between the separate pieces of
carpet along the selvage.

My invention consists of suitable mechan- 60
ism mounted on a table or frame A A A. Un-
der this frame and upon the support b and
by means of the shaft or spindle b' is mount-
ed the roll of carpet B the selvage edges of
which are to be singed or trimmed, the rough 65
edges of the selvage being most distinctly
shown in Fig. 2 of the accompanying draw-
ings. From the roll the carpet is drawn un-
derneath the footboard D, upon which the
workman operating the machine may stand, 70
thence over the loosely-revolving rolls c c'
c² c³, and thence to any suitable mechanism
for shearing the carpet ready for the market.
The loosely-revolving rolls c c' c² are mounted
in suitable supports, as shown, on the frame 75
or table A. On the top of the frame A are
two cross-bars E E, having the slots e e, in
which slots move the selvage-protectors F F.
The carpet B in passing through the machine
is made to pass through the slots or grooves 80
in these two selvage-protectors F F, the shape
of the protectors being such as to leave ex-
posed only the selvage of the carpet, and
this only for a suitable length or distance,
so that the gas-flame only operates on the 85
selvage for an instant. In order that the
selvage-protectors may accommodate them-
selves to any width of carpet and to the
usual irregularities in width of the same piece
of carpet at different portions of its length, 90
they are mounted so as to slide upon the cross-
supports E E within the slots e e, as is dis-
tinctly shown in Fig. 3 and in detail in Fig.
4. A cord or string f unites the two selvage-
protectors, and to this cord is hung a suitable
weight f', which causes the necessary tension 95
upon the cord f, so as to draw the selvage-
protectors F F against the edges of the car-
pet, while yet permitting them to accommo-
date themselves to variations in width of the
carpet. The selvage-protectors at the point 100
nearest the gas-flame rise above the surface

of the carpet, so as to prevent the gas-flame from playing over the pile-surface and so as to confine its operation to the selvage edges.

Two ordinary gas-pipes H H are mounted 5 one at each side of the framework of the machine. To the top of each of these gas-pipes is attached a jointed bracket h h', which ends in an ordinary Bunsen burner, giving a smokeless flame. To the bracket-arms nearest the gas-flame are attached the pivoted levers h² h², which are pivoted at their point of connection with the frame h³. This frame h³ moves in the slots or depressions h⁴ h⁴. When the machine is not in operation or when it is desired to remove the gas-flames, so that they do not play upon the selvage of the carpet, the frame h³, as shown in Fig. 3, is pushed by the operator forward, when by means of the jointed connections h, h', and h² the gas-flame or the nozzle from which it issues is pushed into the position shown in Fig. 3. When it is desired to have the gas-flame play upon the selvage, the frame h³ is drawn back into the position shown in Fig. 2, when by reason of the same jointed connection the gas-flame is brought into position so as to play directly upon the selvage as it passes through the selvage-protectors F F, as shown in Fig. 2.

I have found that the process of singeing or trimming the selvage just described leaves so little charred material that ordinary handling incident to the subsequent shearing of carpet effectually removes it; but if it is considered in any way necessary to brush off the calcined portions of the pile at the selvage it is evident that an ordinary small brush can be screwed or mounted on any portion of the

frame A where its bristles will be in position to act upon the selvage, so as effectually to remove any burned or calcined portions of the 40 pile.

What I claim as my invention, and wish to secure by Letters Patent, is—

1. In a selvage-singeing machine, the adjustable gas-brackets and selvage-protectors 45 combined and operating substantially as described.

2. In a selvage-singeing machine, the adjustable gas-brackets and the selvage-protectors, F, F, with means, as the cord and weight, 50 f, f', automatically to adjust the protectors to varying widths of carpet, substantially as described.

3. In a selvage-singeing machine, the gas-brackets, h', h', the adjusting-levers, h², h² 55 and frame h³, in combination with the automatic adjusting selvage-protectors F, F, moving in the slots e, e, situate on the bars E, E, substantially as and for the purposes described. 60

4. In a selvage-singeing machine, the cross-bars E, E, with the slots, e, e, the selvage-protectors, F, F, and means, as the cord and weight, f, f', automatically to adjust the protectors to varying widths of carpet. 65

In testimony that I claim the foregoing as my invention I have signed my name, in presence of two witnesses, this 5th day of April, 1897.

JAMES EUGENE COCHRANE.
